UNITED STATES PATENT OFFICE.

HUGH W. HARRIS, OF PITTSBURGH, PENNSYLVANIA.

PAPER-FEEDING MECHANISM.

1,294,456.

Specification of Letters Patent. Patented Feb. 18, 1919.

Application filed November 23, 1917. Serial No. 203,477.

To all whom it may concern:

Be it known that I, HUGH W. HARRIS, a citizen of the United States, residing at Pittsburgh, in the county of Allegheny and State of Pennsylvania, have invented certain new and useful Improvements in Paper-Feeding Mechanisms, of which the following is a specification.

In doing mechanical bookkeeping upon a typewriting machine or an adding machine, it is desirable to print the item simultaneously, with the aid of carbon paper, upon the customer's loose-leaf ledger sheet, upon a bill or monthly statement of the customer's account, and upon a proof sheet. However, the spaces in which writing is to be done upon the ledger sheet, the statement and the proof sheet may be, and usually are, at different heights upon the sheets, that is to say, at different distances below the top edges of the sheets. In such case it becomes necessary to assemble the sheets in such a manner that the spaces to be written on upon the three sheets shall be directly superposed in order that the item shall be printed at the proper places upon all three sheets at the same time; in other words, the proper spaces of the several sheets must all be brought to the printing plane of the machine.

Various expedients to effect the desired result above alluded to have been adopted, but all have been troublesome and time-consuming, and therefore have limited the field of usefulness of mechanical bookkeeping and similar operations.

The object of this invention is to provide means whereby the sheets to be printed upon may be fed to the platen in any convenient position and subsequently adjusted, easily and quickly, into the printing plane of the machine, so that the item shall be printed upon the proper spaces of all of the sheets at the same time.

In the accompanying drawings, Figure 1 is a lower side view of the carriage of a machine embodying my invention, the mechanism being shown in position to feed all of the sheets simultaneously. Fig. 2 is a fragmental lower side view of the carriage showing the mechanism in position to feed only the ledger sheet and the proof sheet. Fig. 3 is a similar view showing the mechanism in position to feed only the proof sheet. Fig. 4 is a sectional view on an enlarged scale taken in the plane of dotted line 4-4 of Fig. 1.

In the following description the term

"printing machine" will be used to denote a typewriting machine, an adding and listing machine, or any other machine for printing numerals or letters which employs a rotatable platen. The carriage herein illustrated is adapted to form part of an under-strike printing machine, but it will be understood that the invention is not limited to under-strike machines.

Although the sheets to be printed upon may be supported in any suitable manner, we have herein shown them as mounted in a carriage which may be of the usual or any preferred construction. The carriage which has been selected for illustration comprises two end plates 1 rigidly connected together by means of a front bar 2 and a rear bar 3. 4 is a cylindrical rubber-covered platen provided with a shaft 5, said shaft being rotatably mounted in the end plates 1 of the carriage. While the platen may be of any suitable construction, it is herein shown as of unitary rather than divided construction, the platen being rotatable throughout its entire length by means of either one of the hand wheels 6 carried by the shaft 5.

The paper-guiding means may be of any suitable character. Herein is shown a paper shelf 7 extending from a point behind the platen to a position close to the periphery of the platen a little distance rearwardly of the printing plane. The paper shelf is supported to swing upon the axis of the rod 3. Paper-guiding devices of any desired form and construction may be provided to guide the paper up and around the forward side of the platen. I have herein illustrated spring paper-guiding fingers 8 adjustably mounted upon a front bar 2 and slightly overlapping the lower edge of the paper shelf 7.

To coöperate with the platen in feeding the paper, there is provided a suitable number of feed rolls rotatable independently of each other upon a pivot rod 10. In the drawings the feed rolls are indicated at 9, 9^a, 9^b and 9^c. The rod 10 may be supported in any suitable manner, as by means of arms 11 pivoted upon and extending downwardly from the rod 3. Any desired means may be provided for swinging the arms 11 to move the feed rolls toward and away from the platen. Herein is shown a lever 12 integral with one of the arms 11, depression of which lever serves to move the rod 10 and feed rolls away from the platen. Leaf springs 13 secured to the rod 3 and bearing

upon collars 14 on the pivot rod 10 normally hold the rolls pressed against the paper or the platen, as the case may be. The collars 14 serve to prevent endwise displacement of the feed rolls. The paper shelf 7 has openings 15 therein to allow the feed rolls to make contact with the paper or the platen. The feed rolls are provided in any suitable manner with friction surfaces, as 10 by making the rolls of rubber.

In the drawings, A denotes a proof sheet, B a ledger sheet and C a statement. The statement is narrower than the ledger sheet, and in the present embodiment of the invention the statement is located approximately midway between the side edges of the ledger sheet so as to be engaged by the feed rolls 9^a and 9^b but not by the feed rolls 9 and 9^c. D is a sheet of carbon paper interposed between the proof sheet and the ledger sheet, and E is a sheet of carbon paper between the ledger sheet and the statement. The carbon sheet E is of approximately the same width as the statement, and is of about the 25 same length as the ledger sheet. The carbon sheet D is of about the same length as the proof sheet A. The proof sheet and the carbon sheet D usually remain in the machine until the proof sheet has been filled up. 30 The ledger sheet and the statement for a given customer are inserted into the machine when an item or items for that customer are to be posted, and the ledger sheet and the statement are removed as soon as 35 such items have been posted. In order to permit the withdrawal of the ledger sheet, the carbon sheet E and the statement without disturbing the proof sheet and the carbon sheet D, any suitable means may be employed, as, for example, spring-pressed paper fingers *a* of common construction having rubber-covered rollers *a'*. The fingers *a* are adjustable longitudinally of the bar 2, and in use are positioned so that the rollers *a'* bear upon the side-edge portions of 40 the carbon sheet D. When the feed rolls 9, 9^a, 9^b and 9^c are moved away from the paper by means of the lever 12, the paper fingers *a* prevent the proof sheet and the carbon 45 sheet D from moving while the ledger sheet, the carbon sheet E and the statement are being withdrawn from the machine. As will be understood, the carbon sheet D should be sufficiently wider than the ledger sheet to 50 enable the rollers *a'* to bear upon said carbon sheet.

Each of the three work sheets A, B and C may contain little or much matter, and when inserted into the machine the spaces 55 in which writing should be done on the several sheets must be brought to the printing plane of the machine. This result I accomplish by holding the statement stationary while feeding the ledger sheet and the proof 60 sheet until the proper writing space on the

ledger sheet is in line with the proper writing space on the statement and then holding the statement and the ledger sheet stationary while feeding the proof sheet until the proper writing space on the proof sheet is 70 aligned with the writing spaces on the statement and the ledger sheet. The statement and the ledger sheet may be held stationary by any suitable means while the platen is being turned. If desired, the paper-feeding rolls 9 may be utilized for this purpose; and to this end I have provided means whereby these rolls may be selectively locked against rotation. While various agencies may be employed to hold the feed rolls stationary, I have herein shown a rod 16 slidably and non-rotatably supported in the end plates 1 of the carriage. Adjustably fixed upon said rod are locking collars 17, 17^a, 17^b, 17^c, 17^d and 17^e located adjacent 80 to the ends of the feed rolls and provided with beveled friction surfaces adapted to make contact with the beveled ends of said rolls. The locking collars may be knurled or otherwise adapted to cause friction with the feed rolls. Finger knobs 18 (Fig. 1) fixed upon the ends of the rod 16 provide means for manually reciprocating the rod. When moved in one direction, the friction collars 17^a and 17^e are moved into engagement with the feed rolls 9^a and 9^b to lock said rolls against rotation, the rolls 9 and 9^c being left free to turn. When the rod 16 is moved in the opposite direction, the collars 17, 17^b, 17^c and 17^d are moved into engagement with the rolls 9, 9^a, 9^b and 9^c, respectively, thus holding all of the feed rolls against rotation. The rod 16 is normally held in neutral position by any suitable means, as, for example, coiled expansion 95 springs 19 surrounding the rod and interposed between the end plates 1 and stop collars 20 adjustably fixed upon the rod 16. 100

Assuming that the several sheets are in the machine, the sheets are independently fed until the proper writing spaces on all of the sheets are in alignment. For example, all of the sheets may be fed simultaneously until the proper writing space upon the statement is in the printing plane of the 110 machine. One of the finger-knobs 18 is then operated to move the rod 16 to the right, into the position shown in Fig. 2, and held there by the operator, thus holding the feed rolls 9^a and 9^b (and hence the statement) against movement while the platen is being rotated by means of one of the hand wheels 6. When the platen is rotated, the platen and the feed rolls 9 and 9^c cause the proof sheet and the ledger sheet to move together until the proper writing space upon the ledger sheet is in the printing plane of the machine, the statement sheet C being meanwhile held stationary because there is greater friction between the rubber feed rolls 9^a and 9^b. 115 120 125 130

and the statement sheet C than between the statement sheet C and the carbon sheet E. The operator then moves the rod 16 toward the left into the position shown in Fig. 3 5 and holds the rod in such position while rotating the platen 4 until the desired space upon the proof sheet is in the printing plane of the machine, the ledger sheet and the statement being meanwhile held against movement by means of the feed rolls. There is 10 greater friction between the rubber feed rolls 9, 9^a, 9^b and 9^c on the one hand, and the ledger sheet B and the statement sheet C on the other hand, than there is between the 15 ledger sheet B and the carbon sheet D. Hence, when the feed rolls 9, 9^a, 9^b and 9^c are locked against rotation, the ledger sheet B and the statement sheet C will be held against movement while the proof sheet A 20 is being fed through the friction between said proof sheet A and the platen. When the ledger sheet is being fed independently of the statement, the carbon sheet E moves with the ledger sheet B by reason of the friction 25 between said sheets B and E. Likewise, when the proof sheet A is being fed independently, the friction between the proof sheet and the carbon sheet D suffices to cause the carbon sheet D to move with the proof sheet A.

After the sheets A, B and C have been properly adjusted with reference to one another, they may be simultaneously fed in either direction, for line-spacing and other 35 purposes, by turning the platen and leaving the feed rolls free to rotate.

It will be seen that in the selective feeding operation just described, the rolls, 9, 9^a, 9^b and 9^c act at times as feed rolls and at 40 other times as holding or detaining devices, the rolls being well adapted to perform the last mentioned function by reason of the frictional characteristic of their rubber peripheries and by reason of the pressure exerted by the springs 13. It will be understood, however, that the invention is not limited to the use of feed rolls as the holding 45 means, and that other devices may be employed to hold one or more of the sheets while the remaining sheet or sheets are being 50 adjusted.

As will be apparent from Fig. 1, after the desired printing spaces on the three work sheets A, B and C have been brought into 55 the printing plane, printing may be done upon the ledger sheet alongside the statement and on the right-hand margin of the proof sheet by feeding the carriage from right to left in the usual manner.

To aid in imparting a clear understanding of the invention, I have herein disclosed it in connection with a specific form of mechanical bookkeeping, but I would have it understood that the invention is applicable 60 to various sorts of manifolding or multiple

operations capable of being performed upon typewriters, adding machines and similar devices.

I claim as my invention:

1. A printing machine having, in combination, a rotatable platen to receive a plurality of superposed sheets, the outermost sheet being narrower than the other sheet, a rotatable feed roll yieldingly pressed against the narrow sheet, a rotatable feed 70 roll yieldingly pressed against the wide sheet, and means for selectively preventing rotation of the feed rolls.

2. A printing machine having, in combination, a rotatable platen, a plurality of 80 independently rotatable feed rolls yieldingly pressed toward the platen, a longitudinally reciprocatory rod, a device on said rod to frictionally engage one end of one of the rolls to prevent rotation thereof when the 85 rod is moved in one direction, and a device on the rod to engage one end of another of said rolls to prevent rotation thereof when the rod is moved in the opposite direction.

3. A printing machine having a frame, a 90 platen rotatably mounted in the frame, a plurality of independently rotatable feed rolls for pressing paper against the lower portion of the platen, a rod mounted in the carriage below the platen for longitudinal 95 reciprocation, and means on said rod to engage the rolls to prevent rotation of the latter.

4. A printing machine having, in combination, a rotatable platen, a pivot rod, a 100 plurality of feed rolls mounted upon said rod for independent rotation, means to press the feed rolls toward the platen, and means for preventing rotation of one of the rolls.

5. A printing machine having, in combination, a unitary rotatable platen to receive a plurality of sheets, a feed roll to 105 press one of the sheets against the platen, a feed roll to press another of the sheets against the platen, and means for selectively preventing rotation of the feed rolls.

6. A printing machine having, in combination, a unitary rotatable platen to feed a group of superposed sheets, and pressure means frictionally engaging the outer surface of the group of sheets and pressing the group toward the platen to hold stationary the part of the group engaged by said means while another part of said group is being fed by the platen.

7. A printing machine having, in combination, a unitary rotatable platen to feed a plurality of superposed sheets consisting of an outer sheet, an intermediate sheet and an inner sheet, and pressure means frictionally engaging the outer sheet to hold such sheet stationary while the other sheets are being fed by the platen.

8. A printing machine having, in combination, a unitary rotatable platen to feed a 130

- plurality of superposed sheets consisting of an outer sheet, an intermediate sheet and an inner sheet, the outer sheet being narrower than the other sheets, and means to hold the outer and intermediate sheets stationary while the inner sheet is being fed by the platen.
9. A printing machine having, in combination, a rotatable platen to feed a plurality of superposed sheets consisting of an outer sheet, an intermediate sheet and an inner sheet, the outer sheet being narrower than the other sheets, and pressure means frictionally engaging the outer and intermediate sheets to hold such sheets stationary while the inner sheet is being fed by the platen.
10. A printing machine having, in combination, a rotatable platen to receive a plurality of superposed sheets consisting of an outer sheet, an intermediate sheet and an inner sheet, the outer sheet being narrower than the other sheets, a device to hold the outer sheet stationary, and a device to hold the intermediate sheet stationary, the first mentioned holding device being operable independently of the other.
11. A printing machine having, in combination, a unitary rotatable platen to receive a plurality of superposed sheets, the outermost sheet being narrower than the other sheets, a device to hold the outermost sheet stationary, and a device to hold another of said sheets stationary, the first mentioned holding device being operable independently of the other.
12. A printing machine having, in combination, a rotatable platen to receive a plurality of superposed sheets, the outer sheet being relatively narrow, a device to hold the outer sheet stationary, and a device to hold another of the sheets stationary, said holding devices being located at the same side of the platen.
13. A printing machine having, in combination, a unitary rotatable platen to feed a plurality of superposed sheets, and pressure means frictionally engaging one of said sheets to hold such sheet stationary while the sheets beneath it are being fed by the platen.
14. A printing machine having, in combination, a rotatable platen to feed a plurality of superposed sheets, the outer sheet being narrower than the other sheet, and pressure means frictionally engaging the outer sheet to hold such sheet stationary while the other sheet is being fed by the platen.
15. In a printing machine, a platen, a feed roll, means for pressing the roll toward the platen, and manually-operative means for engaging and holding said roll against rotation in either direction.
16. A printing machine having a platen, a plurality of feed rolls at the same side of the platen, and means for selectively preventing the rotation of said rolls.
17. A printing machine having, in combination, a platen, a paper shelf for directing to the platen a plurality of superposed sheets of different widths, and sheet detaining devices including parts extending through openings in said shelf and adapted to engage exposed portions of a plurality of said sheets.
18. A printing machine having a platen, a paper shelf, a plurality of feed rolls extending through openings in said shelf and means for selectively preventing the rotation of said rolls.
19. A printing machine having a rotatable platen, a paper shelf for directing to the platen a plurality of sheets, and a device including a part projecting through the paper shelf for detaining one of the sheets when the platen is rotated.
20. A paper carriage for printing machines having, in combination, a framework, a platen rotatably mounted in said framework, a pivot rod mounted to swing in the framework, springs urging said pivot rod toward the platen, independently rotatable feed rolls on said rod, a manually operable part supported in the framework, and devices on said part for engaging the feed rolls to prevent rotation of the latter.
21. A paper carriage for printing machines having, in combination, a framework, a platen rotatably mounted in said framework, a pivot rod mounted to swing in the framework, springs urging said pivot rod toward the platen, independently rotatable feed rolls on said rod, a manually reciprocal rod supported in the framework parallel to the pivoted rod, and devices on said reciprocal rod for engaging the feed rolls to prevent rotation of the latter.
22. A paper carriage for printing machines having, in combination, a framework, a platen rotatably mounted in said framework, a rod mounted to swing in the framework, springs urging said rod toward the platen, feed rolls on said rod, and means supported in the framework for engaging the feed rolls to prevent rotation of the latter.
23. A paper carriage for printing machines having, in combination, a framework, a platen rotatably mounted in said framework, a rod mounted to swing in the framework, springs urging said rod toward the platen, feed rolls on said rod, and means for selectively preventing rotation of the feed rolls.

In testimony whereof, I have hereunto set my hand.

HUGH W. HARRIS.
